UNITED STATES PATENT OFFICE.

MARION DORSET, OF WASHINGTON, DISTRICT OF COLUMBIA.

MANUFACTURE OF HOG-CHOLERA ANTITOXIN.

No. 823,110.

Specification of Letters Patent.

Patented June 12, 1906.

Application filed February 7, 1906. Serial No. 300,023.

To all whom it may concern:

Be it known that I, MARION DORSET, a citizen and officer of the United States, residing at Washington, in the District of Columbia, have invented certain new and useful Improvements in the Manufacture of Hog-Cholera Antitoxin, of which the following is a specification.

Hog-cholera is a highly-fatal contagious disease of swine, acute or subacute, characterized by a fever and usually by petechial lesions of any or all of the tissues and organs of the body and by ulcerations of the mucosa of the gastro-intestinal tract, as well as by infectiveness of the blood of sick animals when injected subcutaneously and by immunity in those animals which recover. Heretofore methods for the cure of hog-cholera have been based upon the cultivation of particular bacilli and the injection of their products into the system of the animal to be treated or their administration by the mouth in food or otherwise.

This application is made under the act of March 3, 1883, chapter 143, and the invention herein described and claimed, if patented, may be used by the Government of the United States or any of its officers or employees in prosecution of work for the Government or by any other person in the United States without the payment of any royalty thereon.

My invention consists in the production of a substance called "hog-cholera antitoxin," by means of which pigs may be immunized against hog-cholera and pigs suffering from hog-cholera may be cured.

In order to obtain this antitoxin, I proceed by one or both of the following methods, designated, respectively, as the "quick" method and the "slow" method. In the quick method I select a pig free from hog-cholera which weighs one hundred (100) pounds, more or less, and which is immune from any cause from hog-cholera. I inject this immune test pig subcutaneously with one thousand cubic centimeters, more or less, of defibrinated blood obtained from pigs sick of hog-cholera, the exact amount to be injected depending upon the size of the immune test pig, virulence of the blood, &c. Inasmuch as this pig has received a very large dose it should be allowed to remain undisturbed for eighteen or twenty days or longer, if necessary, when blood-drawings may be made according to the method hereinafter described

for drawing and preserving blood from immune test pigs treated by the slow method.

Under the slow method the procedure is varied from that described under the quick method; but the essential features are the same, being as follows, it being understood that certain animals, herein called "immunes," are incapable of contracting hog-cholera by the usual processes of infection. I select a pig free from hog-cholera weighing one hundred (100) pounds, more or less, and which is immune from hog-cholera from any cause, inject this pig subcutaneously with one hundred cubic centimeters of defibrinated blood from a pig sick of hog-cholera, the dose being graduated according to the conditions which may obtain at the time of the experiment. At the end of a week or ten days, or when the pig has recovered from any reaction that may follow the injection, administer another dose of two hundred and fifty cubic centimeters, more or less, of blood obtained from pigs sick of hog-cholera. After recovery from the second injection—say in a week or ten days—make a third injection, this time using five hundred cubic centimeters, more or less, of blood of a pig sick of hog-cholera. A week or ten days after the last injection, or when the immune test pig has thoroughly recovered, blood may be drawn according to the following method:

Method of obtaining and preserving blood drawn from treated immunes.—Blood may be drawn from the pig which has been treated by the method hereinbefore described, by making an incision into the tail of the immune and then collected in sterilized receptacles and defibrinated. Blood may be drawn at intervals of one week, securing the blood, if more convenient, from other blood vessels. If necessary, the animal may be bled to death by inserting a canula into the heart. This blood, defibrinated, may be preserved as such or it may be centrifugalized, and the serum separated from the red-blood cells. Whether the serum or the whole defibrinated blood be employed sufficient carbolic acid or other suitable preservative should be used to prevent decomposition upon standing. Blood may be drawn at intervals until it possesses insufficient protective value. At this point the animal should be re-injected with diseased blood in a manner similar to that first employed.

Method of making protective inoculations.—After the antitoxic serum or defibrinated

blood from the treated immune has been prepared in the manner hereinbefore indicated pigs which it is desired to protect should be treated as follows, using blood or serum from the immune pig treated by the quick method or the slow method, according to preference. Inject subcutaneously each of the pigs which are to be protected with ten cubic centimeters, more or less, of the treated immune blood or serum, and at the same time on the other side of the body of each pig inject one minimum lethal dose of diseased blood obtained from a pig suffering from hog-cholera. If this method is carefully followed, healthy pigs treated in this manner will thereafter be protected and rendered immune from an attack of hog-cholera. As variations of this method the blood of pigs sick of hog-cholera and blood of pigs rendered immune to hog-cholera by my method or by other causes, may be mixed together before injection into the pig which it is desired to protect, or the blood obtained from treated immune pigs may be injected alone entirely without the use of blood of pigs sick of hog-cholera. These and many other variations of the process may be employed; but in all cases the underlying principle is the same—namely, the injection of a test pig immune from hog-cholera from any cause with blood of a pig sick of hog-cholera, producing in the blood of that immune test-pig an antitoxin, and when this antitoxin is drawn from the immune pig and obtained in the form of a serum or defibrinated blood it is capable, either when used alone or in connection with injections of blood of pigs sick of hog-cholera, of protecting pigs from hog-cholera and preventing them from becoming infected with the disease.

The antitoxic serum or defibrinated blood produced as hereinbefore described may also be used to treat pigs which are already sick of hog-cholera by injecting the sick pigs subcutaneously with the antitoxic serum or defibrinated blood obtained as hereinbefore described with doses varying according to the size of the pig treated and the potency of the particular serum or defibrinated blood. One

or more injections should be made in the manner hereinbefore described, according to 50 results obtained from the first injection.

What I claim as my invention is—

1. The process of producing hog-cholera antitoxin, which consists in inoculating pigs immune from hog-cholera, from any cause, 55 with defibrinated blood obtained from pigs sick of hog-cholera, so as to hyperimmunize the treated test pig, and to form in the blood protective substances for preventing the disease known as hog-cholera, drawing off the 60 blood from the said treated test pigs and separating the serum from the blood corpuscles and preparing the former for use by adding a preservative substantially as described.

2. The process of producing hog-cholera 65 antitoxin which consists in inoculating pigs immune to hog-cholera from any cause, with defibrinated blood obtained from pigs sick of hog-cholera so as to hyperimmunize the treated test pig, and repeating the injection 70 with larger injections of blood obtained from pigs sick of hog-cholera, then drawing off the blood from the said treated test pigs, separating the serum from the blood corpuscles and adding a preservative, substantially as 75 described.

3. As a new substance hog-cholera antitoxin, consisting of the blood of pigs, rendered immune from hog-cholera from any cause, treated with blood obtained from pigs 80 sick of hog-cholera, and having the characteristics of immunizing pigs against infection from hog-cholera and curing those artificially infected with hog-cholera, and adapted to be used either alone, or in connection with 85 injections of the blood of pigs sick of hog-cholera to prevent the disease known as hog-cholera in healthy pigs, and to cure pigs sick of hog-cholera.

In testimony that I claim the foregoing as 90 my invention I have signed my name in the presence of two subscribing witnesses.

MARION DORSET.
